(57) **CLAIM**

I claim the ornamental design for a bottle, as shown and described.

DESCRIPTION

FIG. 1 is a perspective view of a bottle showing the new design;

FIG. 2 is a front view thereof, with the rear view of the design being a mirror image of the front;

FIG. 3 is a left side view thereof;

FIG. 4 is a right side view thereof;

FIG. 5 is a top view thereof; and,

FIG. 6 is a bottom view thereof.

The broken lines shown are included for the purpose of illustrating portions of the *** that form no part of the claim.
